United States Patent Office

Des. 214,956
Patented Aug. 12, 1969

214,956

MAGNIFIER

Saint Barth Alaska, 3811 Scoville Ave.,
Berwyn, Ill. 60402

Filed June 6, 1968, Ser. No. 12,236

Term of patent 14 years

Int. Cl. D16—08

U.S. Cl. D57—1

FIG. 1

FIG. 2

FIG. 3

FIG. 4

FIG. 5

FIG. 1 is a front elevation of a magnifier showing my new design;

FIG. 2 is a rear elevation thereof;

FIG. 3 is a top plan view thereof;

FIG. 4 is a front elevation of a modified embodiment of the magnifier shown in FIG. 1; and

FIG. 5 is a front elevation of a further modified embodiment of the magnifier shown in FIG. 1.

The broken lines representing the zodiac signs are shown for illustrative purposes only.

I claim:

The ornamental design for a magnifier, as shown and described.
